UNITED STATES PATENT OFFICE.

ISAAC LAVENSON, OF PHILADELPHIA, PENNSYLVANIA.

DESIGN FOR A CIGAR-SIGN.

48,752.

Specification for Design.

Patented Mar. 21, 1916.

Application filed January 20, 1916. Serial No. 73,257. Term of patent 3½ years.

To all whom it may concern:

Be it known that I, ISAAC LAVENSON, a citizen of the United States, residing in the city and county of Philadelphia, State of Pennsylvania, have invented a new, original, and ornamental Design for a Cigar-Sign, of which the following is a specification, reference being had to the accompanying drawing, forming part thereof.

The figure is a face view of a cigar sign showing my new design.

I claim:—

The ornamental design for a cigar sign substantially as shown.

ISAAC LAVENSON.

Witnesses:

JOHN A. WIEDERSHEIM,
N. BUSSINGER.
